SAFETY RAZOR

Walter Robinson Swann, Sheffield, England, assignor to W. R. Swann & Company Limited, Sheffield, England, a corporation of Great Britain

Application January 15, 1942, Serial No. 426,831
In Great Britain July 14, 1941

4 Claims. (Cl. 30—74.1)

This invention relates to safety razors or safety razor blade holders of the kind in which a thin double-edged blade is flexed to a position of transverse curvature between fixed and movable blade flexing members of a blade accommodating head.

The object of this invention is to provide an improved safety razor holder of the before indicated kind which although it will be of a simple construction so as to be economical to manufacture, will be efficient in use, easy to clean after use, and permit of easy insertion and removal of the blade without the necessity for elaborate positioning means therefor, a special object of the invention being to provide a razor blade holder having fixed members forming slots for receiving and exposing the edges of a double-edged blade and in which slots the blade edges are supported and exposed throughout their entire length, while the convex side of the blade is exposed between said fixed slot-forming members.

Referring to the drawing filed herewith—

Fig. 1 is an elevation of one form of razor made according to this invention, the blade being unflexed.

Fig. 2 is a vertical sectional part end view thereof.

Fig. 3 is a plan, the blade being omitted.

Fig. 4 is a sectional elevation with the blade flexed into the operative position for shaving.

Fig. 5 is a vertical sectional part end view, and Fig. 6 is a plan.

2 is the blade receiving and clamping head formed integral with a hollow handle 3. The opposite longitudinal outer edges 4 of the said head are each formed as a guard to the cutting edges of the blade 5. Spaced above the guard 4 in fixed relation thereto and integral therewith, or attached thereto, are separate fixed blade flexing members 6 located for contact of the upper face of the blade 5, one each adjacent the cutting edges thereof. A slot or opening 7 is thereby formed between the blade guard 4 and blade flexing member 6 at each side of the head 2 within which the cutting edge of the blade 5 functions.

The blade receiving and clamping head 2 is recessed intermediate of its edges to form a guideway 8 for a movable blade carrying and flexing member 9. This movable blade flexing member is provided with a plurality of blade positioning studs 10 on its upper face whereby the blade 5 is disposed between the fixed blade

flexing members 6 and the movable blade flexing member 9.

Projecting from the under face of the movable blade carrying and flexing member 9 is a stem 12 which extends down the hollow handle 3, the said handle serving as a guide for the stem.

An intermediate length 13 of the stem near its lower end is of reduced diameter and externally screw threaded while the remaining length 14 therefrom to its extremity is of further reduced diameter. Engaging the screw threaded length 13 of the stem 12 is an internally screw threaded hollow spindle 15 which is rotatably held in the handle 3 by a small set screw 16 screwed into the handle and projecting into an annular recess 17 in the spindle 15.

An integral operating head 18 to the spindle 15 abuts the extremity of the handle 3 and forms continuity therewith. Rotation of the head 18 effects axial traverse of the stem 12 for raising or lowering the movable blade flexing member 9 according to the direction of rotation given to the head. This head 18 is of increased bore at the orifice to form an inner shoulder 19 for the contact of a washer 20 secured to the extremity of the stem 12 by a set screw 21 and thereby serving as a stop for limiting the axial traverse of the stem in raising the movable blade flexing member 9.

As will be seen, rotation of the spindle head 18 in the appropriate direction axially traverses the stem 12 to effect rising movement of the movable blade carrying and flexing member 9 and cause the blade 5 to be carried therewith and into contact with the fixed blade flexing members 6 whereby the blade is flexed to a position of transverse curvature to the desired degree and as determined by the extent of rotation of the spindle head 18. Reverse rotation of the head retracts the movable blade carrying and flexing member 9 and withdraws the blade 5 out of contact with the fixed blade flexing members 6.

It will be seen that the relation of the fixed blade flexing members 6 to the blade guard 4 remains constant and since the blade, near its cutting edge, flexes with a lever action against the said flexing members 6 under the pressure of the movable blade flexing member 9, the particular relation of the blade edge to the guard can be readily adjusted or varied to suit the convenience of the user by the desired rotation of the spindle head 18 so as to increase or decrease the pressure upon the blade 5 and consequently

the angular location of the blade edges with respect to the guard. This provision for adjustment of the cutting edge also permits the use of blades of different thickness to be used with equal efficiency.

The movable blade flexing member 9 may be of any suitable shape designed to permit, in conjunction with the fixed blade flexing members 6, the maximum of freedom for flexure of the blade 5.

It is to be understood that the invention is not to be limited to the particular construction shown, the illustrations depicted in the accompanying drawing being by way of example only. Furthermore, any known or other convenient form of positioning means for the blade found to be suitable and other than that shown, may be employed.

What I claim and desire to secure by Letters Patent is:

1. A safety razor blade holder comprising a handle, a blade accommodating head attached to said handle and incorporating a fixed blade guard and associated fixed blade flexing member spaced from said guard in fixed relation thereto at each of two opposite sides of said head to provide permanent blade edge receiving and exposing slots between said guard and said member longitudinally of said head, the fixed blade flexing members being spaced from each other to provide a permanent blade exposing opening in said head, and hand manipulable means including a movable blade flexing member movable away from the blade accommodating head to move a blade and hold it in a fixed position of transverse curvature against the fixed blade flexing members with the convex side of said blade exposed in said opening and with the cutting edges of said blade supported for use in the blade edge receiving and exposing slots throughout the length of said edges.

2. A safety razor blade holder comprising a handle, a blade accommodating head attached to said handle and incorporating a fixed blade guard and associated fixed blade flexing member spaced from said guard in fixed relation thereto at each of two opposite sides of said head to provide permanent blade edge receiving and exposing slots between said guard and said member longitudinally of said head, the fixed blade flexing members being spaced from each other to provide a permanent blade exposing opening in said head, a movable blade flexing member slidably operable in a guide in the blade accommodating head and movable away therefrom for flexing a blade and holding it in a fixed position of transverse curvature against the fixed blade flexing members with the convex side of said blade exposed in said opening and with the cutting edges of said blade supported for use in the blade edge receiving and exposing slots throughout the length of said edges, said movable blade flexing member having an attached actuating

stem extending into the handle, and hand manipulable means rotatably accommodated in said handle for operating said stem.

3. A safety razor blade holder comprising a handle, a blade accommodating head attached to said handle and incorporating a fixed blade guard and associated fixed blade flexing member spaced from said guard in fixed relation thereto at each of two opposite sides of said head to provide permanent blade edge receiving and exposing slots between said guard and said member longitudinally of said head, the fixed blade flexing members being spaced from each other to provide a permanent blade exposing opening in said head, a movable blade flexing member slidably operable in a guide in the blade accommodating head and movable away therefrom for flexing a blade and holding it in a fixed position of transverse curvature against the fixed blade flexing members with the convex side of said blade exposed in said opening and with the cutting edges of said blade supported for use in the blade edge receiving and exposing slots throughout the length of said edges, said movable blade flexing member having an attached actuating stem extending into the handle, hand manipulable means rotatably accommodated in said handle for operating said stem and means in said handle for limiting movement of the movable blade flexing member away from the blade accommodating head.

4. A safety razor blade holder comprising a handle, a blade accommodating head attached to said handle and incorporating a fixed blade guard and associated fixed blade flexing member spaced from said guard in fixed relation thereto at each of two opposite sides of said head to provide permanent blade edge receiving and exposing slots between said guard and said member longitudinally of said head, the fixed blade flexing members being spaced from each other to provide a permanent blade exposing opening in said head, a movable blade flexing member slidably operable in a guide in the blade accommodating head and movable away therefrom for moving a blade and holding it in a fixed position of transverse curvature against the fixed blade flexing members with the convex side of said blade exposed in said opening and with the cutting edges of said blade supported for use in the blade edge receiving and exposing slots throughout the length of said edges, said movable blade flexing member having an attached actuating stem extending into the handle, hand manipulable means rotatably accommodated in said handle for operating said stem, means in said handle for limiting movement of the movable blade flexing member away from the blade accommodating head, and means on said movable blade flexing member for correctly positioning a blade thereon in relation to the blade edge receiving and exposing slots.
